(57) **CLAIM**

The ornamental design for a lane light, as shown and described.

DESCRIPTION

FIG. 1 is a perspective view of a lane light showing our new design;

FIG. 2 is a front view thereof, the back view being identical; FIG. 3 is a right side view thereof, the left side view being identical;

FIG. 4 is a top view thereof;

FIG. 5 is another perspective view of the lane light of FIG. 1, but shown with different broken line subject matter; FIG. 6 is a front view of FIG. 5, the back view being identical;

FIG. 7 is a right side view of FIG. 5, the left side view being identical; and,

FIG. 8 is a top view of FIG. 5.

The broken dash-dot-dash lines emanating from the bottom of the lane light represent illumination and form no part of the claimed design. The dash-dash-dash broken lines shown in the drawings are included for purposes of illustrating portions of the lane light and form no part of the claimed design.
